UNITED STATES PATENT OFFICE.

EDWIN C. WEISGERBER, OF THE UNITED STATES ARMY.

FUSE-PLUG.

1,346,574.

Specification of Letters Patent. Patented July 13, 1920.

Application filed February 19, 1919. Serial No. 277,980.

(FILED UNDER THE ACT OF MARCH 3, 1883, 22 STAT. L., 625.)

To all whom it may concern:

Be it known that I, EDWIN C. WEISGERBER, Capt. corps of engineers, a citizen of the United States, stationed at Washington, 5 District of Columbia, have invented an Improvement in Fuse-Plugs, of which the following is a specification.

The invention described herein may be used by the Government, or any of its officers or 10 employees in prosecution of work for the Government, or by any other person in the United States, without payment of any royalty thereon.

My invention relates to improvements in 15 fuse plugs, and refers particularly to what are commonly known as refillable fuse plugs, used in connection with electric-lighting systems, although they are not necessarily limited to such service.

20 One object of my invention is the provision of a refillable fuse plug which will allow instant application and removal of the fuse-strip or conductor from the exterior of the fuse proper, without interfering with the parts of the plug, thus permitting the renewal of the fuse-strip when found necessary with ease and facility and at the same time saving the main parts which constitute the fuse plug as a whole.

30 Another object of my invention is the provision of a refillable fuse plug which will permit exterior access to the fuse strip or conductor and which will locate or dispose the constituent elements of the plug in the 35 most compact and satisfactory relation to secure the best possible results.

Another object of my invention is a provision of a refillable fuse plug which will possess merit in point of simplicity, will be 40 inexpensive of production and which will prove absolutely reliable and practical in every particular.

With the attainment of the stated objects in view, the invention consists broadly of a 45 fuse plug, comprising a hollow porcelain or insulating body, a fuse-strip or conductor disposed within the hollow body and having its terminals passing substantially to the exterior of the body, and exteriorly accessible means for securing the terminals in proper electrical contact relation.

The invention further consists of a refillable fuse plug, embodying certain features of construction, combination and arrangement of parts for service, substantially as

shown, described and particularly defined by the claims, the right being reserved to make any change or modification which falls within the spirit of the invention as distinguished by the claims.

60

In order that the details of construction and the operation of my refillable fuse plug may be readily understood and the advantages accruing from such construction be fully appreciated, I have shown in the accompanying drawing a fuse plug or conductor constructed according to my invention.

Figure 1 represents a side elevation of a 70 refillable fuse plug embodying my improvements;

Fig. 2 represents a central vertical sectional view thereof;

Fig. 3 represents a bottom plan view of 75 the improvement, the clamp disk removed;

Fig. 4 represents a sectional view taken on the line 4—4, of Fig. 2; and

Fig. 5 represents a plan view of the blank 80 forming the fuse-strip or conductor employed in my refillable fuse plug.

The fuse plug in general appearance is not essentially different from fuse plugs of this character in general use and comprises a hollow porcelain or insulating body composed of the shouldered base portion A, the 85 intermediate portion B, and the conical reduced portion C, the said reduced portion being open and provided with an internal rib D, and a pair of oppositely disposed seats or recesses E, whose function or purpose will presently appear, while the exterior of the intermediate portion of the insulating body is provided with threads F, to receive the threaded metal shell conductor G, said enlarged base portion A, of the body being 90 provided with the usual transparent or mica window or covering H, retained in place by the cap H'. The cap H' has a close binding fit on the body of the plug or may be secured thereon in any usual and well known 100 manner.

Fitting in the opening of the restricted portion C, of the hollow insulating body is a metal disk J, formed with the pair of lips K, which seats in the recesses E, and is further provided with an opening L, for the passage of the fuse strip or conductor, and has formed thereon the threaded stem M, which receives the disk N, and also the threaded clamping disk O, between which 110

and the disk is clamped one terminal P , of the fuse strip or conductor P' , while the other terminal P'' of said conductor, passes through an opening Q , in the body and is clamped between the conductor shell G , and the threaded bushing R , mounted in a socket R' , in the body, while the clamping screw S , serves to hold the terminal P'' , of the fuse strip or conductor in operative relation to the shell and bushing.

It will thus be apparent that the fuse-strip or conductor is disposed within the hollow insulating body with its terminals disposed in such manner that the removal of the clamping screw and the clamping disk and unscrewing the screws and shell G will permit the instant detachment of a worn fuse strip or conductor and allow the immediate replacement of a new fuse strip or conductor without interference or injury to any part of the fuse plug, and also that the construction disposes the elements which compose the fuse in the most practical relation to secure the best possible results, and that generally the improvements will insure the production of an efficient, desirable, and entirely practical commercial product of this character. It will be understood that a new fuse P' may be easily threaded through the opening L and into the opening Q and the removed parts replaced.

I claim:

1. A refillable fuse plug, consisting of a hollow insulating body formed with an opening in one end and an opening in one wall in aligned relation, a conducting shell carried by said insulating body and having a passage therein, a clamping member mounted in the conducting shell and body, and a fuse-strip or conductor having its terminals clamped in operative position by the conducting shell, and clamping member and by the clamping member mounted in the end of said body.
2. A refillable fuse plug, consisting of a hollow insulating body having an open end and having an opening in one side thereof, a shell conductor on said body disposed relatively to the opening in the side thereof, a clamping member mounted in the open end of the body, and a fuse-strip or conductor

having one terminal secured by said clamping member in the open end of the body and the other passing through the opening in the wall of the body and retained by the 55 said shell conductor.

3. A refillable fuse plug, consisting of a hollow insulating body having an opening in one wall and provided with an open end, a conductor shell mounted intermediately 60 upon the body, a threaded bushing fitting in the body, a binding screw having its threaded portion passing through the conductor shell into said threaded bushing, a clamping member mounted in the open end 65 of the body and provided with an opening, and a fuse-strip or conductor arranged in the hollow body and having its terminals one secured by the clamping member and its other between the bushing and shell by said 70 binding screw.

4. A refillable fuse plug, consisting of a hollow insulating body having a passage in one wall and having an open end formed with recesses, a disk fitting the open end and 75 having lips fitted in said recesses, having a passage therethrough and formed with a threaded stem, a clamping member engaging said threaded stem, a conductor shell mounted upon the body, a threaded bushing 80 fitting in the body contiguous to the passage in the wall thereof, a binding screw in said bushing, and a fuse-strip or conductor disposed in the hollow body with its terminals passing through the passage in the wall and 85 disk, and secured in proper conducting relation by means of said clamping member and binding screw.

5. In a refillable fuse, the combination with a hollow insulating body, having a 90 passage in one end and in one wall, a clamping element rigidly mounted in the open end of said body, a conducting shell and binding screw mounted exteriorly of the body, and a fuse-strip or conductor disposed with 95 in the body and having its terminals one passing through the clamp and secured thereby and its other terminal passing through the opening in the wall of the body and secured by the conductor shell and binding screw.

EDWIN C. WEISGERBER.
